MANUFACTURE OF CHLOROPYRENES

Peter George Carter, Manchester, England, assignor to Imperial Chemical Industries Limited, a corporation of Great Britain

No Drawing. Application December 4, 1945, Serial No. 632,789. In Great Britain December 7, 1944

4 Claims. (Cl. 260—649)

1

This invention relates to the manufacture of chloropyrenes and more particularly it relates to the manufacture of chloropyrenes containing 3 to 4 chlorine atoms from pyrene-containing coal products.

It is known that certain fractions of coal-tar, of hydrogenated coal-tar and of hydrogenated coal contain small quantities of pyrene. The separation of this pyrene on a commercial scale, particularly from fractions containing very small quantities of pyrene, has hitherto presented difficulties arising from the similarity between the physical properties of pyrene and those of the other constituents of the pyrene-containing fractions.

It is also known that tri- and tetra-chloropyrenes may readily be made by chlorination of pyrene but owing to the difficulties attendant on the separation of pyrene from the pyrene-containing fractions tri- and tetra-chloropyrenes have hitherto been relatively inaccessible materials.

This invention is based on the discovery that it is unnecessary in the manufacture of tri- and tetra-chloropyrenes or of mixtures of these substances from pyrene-containing fractions of coal-tar or hydrogenated coal-tar or of hydrogenated coal to isolate the pyrene.

According to the invention we provide a process for the manufacture of tri- and tetra-chloropyrenes or of mixtures of these substances by chlorinating pyrene-containing fractions of coal-tar, of hydrogenated coal-tar or of hydrogenated coal characterised in that the chlorination is carried out in an inert organic solvent in which the chloropyrenes are substantially insoluble at least at atmospheric temperature, but in which preferably the remaining material is soluble, the chloro-pyrenes being separated from the reaction mixture by cooling and filtering.

The pyrene-containing fractions which may be used in the process of the invention include for example fractions of heavy creosote oil, of hydrogenated creosote oil and of heavy anthracene oil but any fraction of coal-tar, of hydrogenated coal-tar, or of hydrogenated coal may be used provided there is pyrene present therein. Chloropyrenes have been obtained by the process of the invention from fractions containing as little as 2% by weight of pyrene.

The chlorination is effected directly, by the passage of chlorine gas into the solution of the pyrene-containing fraction in a suitable solvent. The temperature at which the chlorination is conducted may vary and atmospheric tempera-

2

ture is suitable but it has been found advantageous, prior to the commencement of chlorination, to heat the reaction mixture in a bath at about 100° C. In order to obtain the best results chlorine should be passed in rapidly, for example at a speed of 20 litres per hour per 100 grams of fraction.

The organic solvent used, as said, is inert; that is to say it is a solvent which will not itself be appreciably chlorinated under the conditions of the process. It should be one in which at atmospheric temperature tri- or tetra-chloropyrene or mixtures of these substances are substantially insoluble and, preferably, in which the other material present, both before and after chlorination, is readily soluble. Suitable solvents which have been used successfully include nitrobenzene, bromobenzene, α -chloronaphthalene, tetrachloroethane, benzene, carbon tetrachloride, acetic acid, and α -dichlorobenzene. It may be determined whether a given solvent is suitable by a laboratory small-scale trial.

The proportion of pyrene-containing fraction to solvent is conveniently as high as 1 to 2 or 3 by weight in order that the best yields of chloropyrenes may be obtained. The duration of the passage of chlorine through the reaction mixture may be determined by cooling and filtering off the separated solid from a test-portion of the reaction mixture. When the so-isolated solid does not begin to melt below 310° C. the chlorination is complete. Under certain conditions and particularly when the proportion of pyrene in the pyrene-containing fraction used is fairly high e. g. of the order of 10% by weight it has been found that a record of the temperature changes within the reaction mixture will give an indication of the completion of chlorination since it is observed that the said temperature on commencement of chlorination rises steadily and subsequently falls this fall being followed by a second rise which is accompanied by separation of the chloropyrenes. When the temperature begins to fall a second time the formation of chloro-pyrenes is complete and chlorination may be discontinued.

The separated solid deposit of chloropyrenes may be filtered from the residual liquid material after cooling the reaction mixture to about atmospheric temperature. It may thereupon be washed, conveniently first with the solvent used in the chlorination, and preferably subsequently with another lower boiling solvent for example ethanol, and then dried.

When, for example, acetic acid or carbon tetrachloride is used as the solvent the residue may be tarry owing to separation of some insoluble matter

other than chlorinated pyrene. In this event the tarry matter may be removed by washing with for example benzene.

The so-obtained product consists of tetrachloropyrene containing variable proportions of tri-chloropyrene. It is useful for example in the manufacture of higher polychloropyrenes and of naphthalene-1:4:5:8-tetracarboxylic anhydride which are themselves useful as intermediates in the manufacture of vat dyestuffs.

The invention is illustrated but not limited by the following examples in which the parts are by weight:

Example 1

100 parts by weight of a fraction (B. P. 215-245° C./13 mm.) of heavy creosote oil are dissolved in 300 parts of nitrobenzene, and the mixture is stirred in a boiling water-bath. Chlorine gas is introduced into the solution through a wide tube which dips below the surface of the stirred solution, at a speed of 22-24 litres per hour per 100 grams of fraction. The temperature of the mixture rises, then falls, then again rises; as soon as the temperature begins to fall for the second time the current of chlorine is discontinued. The mixture is stirred in the boiling water-bath for a further 15 minutes, then cooled to 20-30° C., and filtered. The solid residue is washed with nitrobenzene, then with ethanol, and dried. There are obtained 8.22 parts of a cream-coloured solid, M. P. 310-355° C., consisting of a mixture of tri- and tetrachloropyrene.

Example 2

A mixture of 100 parts of the fraction of B. P. 380-400° C. of heavy anthracene oil and 200 parts of nitrobenzene is chlorinated as described in Example 1. 11.4 parts of a mixture of tri- and tetra-chloropyrene are obtained.

Example 3

A mixture of 200 parts of nitrobenzene and 100 parts of the fraction of B. P. 215-245° C./13 mm. of hydrogenated creosote oil is chlorinated as described in Example 1. 21.8 parts of a mixture of tri- and tetra-chloropyrene are obtained.

Example 4

A mixture of 200 parts of commercial o-dichlorobenzene and 100 parts of fraction (B. P. 215-245° C./13 mm.) of heavy creosote oil is chlorinated as described in Example 1. 6.96 parts of a mixture of tri- and tetra-chloropyrene are obtained.

Example 5

A mixture of 300 parts of nitrobenzene and 100 parts of the fraction of B. P. 215-245° C./13 mm. of heavy anthracene oil is chlorinated as

described in Example 1, but at a rate of 7-8 litres of chlorine per hour per 100 g. of fraction. 15.8 parts of a mixture of tri- and tetra-chloropyrene are obtained.

5 I claim:

1. A process for the recovery of pyrene in the form of tri- and tetra-chloropyrenes from fractions of coal tar, hydrogenated coal tar and hydrogenated coal and the production of such chloropyrenes, which comprises passing chlorine into an organic solvent solution of the pyrene containing fraction until the formation of the chloropyrenes in the solution is substantially complete and separating the resulting chloropyrenes from the reaction mixture by cooling and filtering, the organic solvent employed being one which is inert under the conditions of chlorination and in which the chloropyrenes are substantially insoluble at atmospheric temperatures but in which the pyrene containing fraction, from which the pyrene is being extracted in the form of chloropyrenes, is soluble.
- 10 2. The process as defined in claim 1 in which the inert solvent is a chlorinated hydrocarbon.
- 15 3. The process as defined in claim 1 in which the inert solvent is nitrobenzene.
- 20 4. A process for the recovery of pyrene in the form of tri- and tetra-chloropyrene from fractions of coal tar, hydrogenated coal tar and hydrogenated coal and the production of such chloropyrenes, which comprises passing chlorine into a nitrobenzene solution of the pyrene containing fraction while it is maintained at boiling water bath temperature until the formation
- 25 35 of the chloropyrenes in the solution is substantially complete and separating the resulting chloropyrene from the reaction mixture by cooling and filtering, the amount of nitrobenzene employed being, by weight, from 2 to 3 times that of the pyrene containing fraction.
